SWITCH STRUCTURE

Earl J. Dyess, Longview, Tex.

Application May 8, 1934, Serial No. 724,564

1 Claim. (Cl. 173—328)

This invention appertains to new and useful improvements in the general art of circuit makers and breakers, and more particularly to a novel disconnecting plug and receptacle for use in conjunction with commercial electricity service and watthour meter connections.

The principal object of the invention is to provide a quick-detachable plug and receptacle whereby the usual watthour meter and service line connections to a house can be broken conveniently from a point exteriorly of the house by the utility company's employees.

Another important object of the invention is to provide a switch of the character stated which will be substantially waterproof and substantially fool-proof in construction.

These and various other important objects and advantages of the invention will become apparent to the reader of the following specification.

20 In the drawings:

Figure 1 represents a side elevational view of the novel disconnecting device.

Figure 2 represents a vertical sectional view taken substantially on line 2—2 of Figure 1.

25 Figure 3 represents a top plan view of the device, with the cover removed.

Figure 4 represents a bottom plan view of the rotor.

30 Figure 5 represents a front elevational view of one of the brushes.

Figure 6 represents a side elevational view of the rotor.

Figure 7 represents an elevational view of one of the insulation blocks.

35 Figure 8 represents a diagrammatic view showing the electrical connections between the electrical elements and line.

Referring to the drawings wherein like numerals designate like parts, it can be seen in Figure 8, that the arrangement, generally referred to by numeral 5, discloses a diagram of the meter and service disconnecting plug and receptacle showing connections for a two-wire 110 volt watthour meter. The arrangement generally referred to by numeral 6, shows the same disconnecting device hooked up for a three-wire 110-220 volt watthour meter.

By referring to the arrangement generally referred to by numeral 5, it can be seen that the wire 7 extends from the line to the contact 9 of the receptacle, while the wire 10 extends from the contact 11 of the receptacle to form part of the service circuit, including the neutral wire 11 connected with the neutral conductor 12 of the line. Numeral 13 represents a conductor which

connects to the contact 14 of the receptacle and also to the contact 15 of the receptacle. Wires 16—17 extend from the rotor contacts 18—19 to the watthour meter, while numeral 20 represents a neutral wire from the contacts 21—22 of the rotor or plug of the switch to the meter. (Not shown).

In the three-wire type, generally referred to by numeral 6, numeral 23 represents the 220 volt line wire to the receptacle contact 9, while the 10 wires 24—25 extend from the contacts 11—15 of the receptacle, with the neutral conductor 26 to the service entrance. A 220 volt line connection 26 is made to the contact 14 of the receptacle. A 220 volt load wire 27 extends from the 15 watthour meter (not shown) to the rotor of the switch at the contact 19, while a 220 volt line wire from the rotor contact 18 extends to the watthour meter. Numeral 29 represents a 220 volt load wire from the watthour meter to a 20 contact 21 of the rotor, while the contact 22 of the rotor has the 220 volt line wire 30 extending therefrom to the watthour meter.

In describing the construction of this novel switch, it can be seen that the same consists in 25 the construction of a substantially square casing 31, open at its top and provided with a substantially ovate-shaped opening 32 in the bottom thereof. A flanged lid 33 is provided for the casing 31, the flanges of the lid being secured to the 30 casing 31 by screws 34.

At a pair of opposite sides of the casing 31 and at the inside thereof are secured the blocks 35—36, each having secured thereto spring contact brushes, denoted by reference numerals 9, 11, 14 35 and 15. Each of these blocks 35 and 36 is secured to the casing by a screw or bolt 37, while each of the contact brushes has a post extending therefrom and through the casing wall. Each of these posts is threaded and provided with binding nuts 40 38 whereby the wires leading to the contacts can be suitably secured in place. The casing 31 is provided with a bracket 39 whereby the casing and in fact, the entire switch, can be suitably supported for use.

45 In Figure 2, the rotor of the switch is generally referred to by numeral 40 and consists of the tube 41 having a transversely elongated dielectric body 42 thereon, the body being anchored to the tube 41 by anchor pins 43, certain of which 50 project from the ovate-shaped plate 44 at the socket end 45 of the tube 41, this plate 44 being engageable with the body 42 through the ovate-shaped opening 32 in the bottom of the casing 31, while a plate 46 at this socket end 45 of the 55

tube 41 and spaced from the plate 44, prevents excessive inward movement of the rotor. The socket 45 is internally threaded to receive the usual conduit pipe which carries the meter and service wires into the building.

The lower contacts 19-22 are substantially L-shaped as shown in Figure 6, the upstanding portions *a* of which extend upwardly along the di-electric body 42 and have their upper ends bent across a portion of the upper end of the body 42 as to the contacts 18-21, all of these portions of the contacts disposed over the upper end of the body 42 being provided with binding posts 48.

It can now be seen that the only operation required in disconnecting both the meter and the service line is for the employee to grasp the conduit pipe (not shown in the drawings) and rotate the same until the plate and body 42 of the rotor 40 is registering with the ovate-shaped opening 32 in the bottom of the casing 31, at which point the rotor can be pulled downwardly and entirely disengaged from the brushes in the casing 31.

While the foregoing specification sets forth the

invention in specific terms, it is to be understood that numerous changes in the shape, size and materials may be resorted to without departing from the spirit and scope of the invention as claimed hereinafter.

Having described the invention, what is claimed as new is:—

In combination with an electrical conduit, a casing having contact brushes therein, a di-electric head for the conduit, said casing being provided with an opening through which said head can be inserted, said head being provided with contacts for engagement with the said brushes, said head being provided with a tubular conduit section extending therethrough, a base plate on the conduit section against one end of the head, a conduit receiving socket at the end of the conduit section adjacent said base plate, and a flange on the said socket in spaced relation to the base plate, said flange being adapted to limit upward movement of the said head into the casing.

EARL J. DYESS.
